GAS BURNER

Albert Horace Greaves, London, England, assignor
of forty per cent to Ronald Victor Short, Haxby,
England

Application May 27, 1943, Serial No. 488,720
In Great Britain June 16, 1942

4 Claims. (Cl. 158—118)

1

This invention relates to gas burners of the injector type in which the burner jet is arranged centrally within the bell mouthed or enlarged lower end of the mixing tube, the orifice being located in the throat of the mixing tube immediately above the upper edges of the air inlet holes, the jet immediately surrounding the orifice being of part conical shape and in conjunction with the throat providing an intervening annular passage through which air entering the inlet holes must pass to enter the upper part of the mixing tube.

In order that the said invention may be clearly understood and readily carried into effect, the same will now be described more fully with reference to the accompanying drawings, wherein:

Figure 1 is a longitudinal vertical section of a gas burner constructed in accordance with the invention;

Figure 2 is a transverse section on the line II—II in Figure 1;

Figure 3 is a transverse section on the line III—III in Figure 1; and

Figure 4 is an enlarged fragmentary longitudinal sectional detail of the lower part of Figure 1.

In the preferred embodiment of the invention illustrated, the jet 1 having a central orifice 1a is located in position within the lower end of a mixing tube 2 which is provided with radially arranged air admission holes 3 around its periphery, the discharge end of the jet orifice 1a being located at a point slightly above the upper edges of the air admission holes, the portion of the jet immediately surrounding the orifice being of part conical shape.

The interior of the mixing tube 2 immediately above the air admission holes 3 tapers sharply inwardly as at 4 to form the throat and terminates in a parallel sided boring 5, the mixing tube at its upper end 6 being externally of part conical shape. It is preferred that the width x of the annular space 7 separating the part conical surface of the jet from the part conical inner surface or inwardly tapered part 4 of the mixing tube shall be not less than one-sixth and not more than one-third the diameter y of the parallel sided boring 5 in the upper part of the mixing tube.

A second mixing tube 8 is maintained in spaced relationship with the first mixing tube 2 by engagement of the lower threaded end of the tube 8 with the internal threads of a flange-like sleeve 9 on the upper end of the tube 2. The sleeve 9 is provided with air admission holes 10 around its periphery, the air entering the second mixing tube through the annular space 11 surrounding the part conical extremity 6 of the first mixing tube and the lower edge 12 of the second mixing tube.

2

The second mixing tube is shaped interiorly as at 13 in the form of a venturi, the constriction 8a being situated at a point near the extremity of the first mixing tube, said extremity 5 being situated at a point between the constriction 8a and the upper edges of the holes 10, the internal bore of the second mixing tube progressively increasing from the constriction to its extremity 14 which constitutes the burner mouth or alternatively leads to a separate gas burner or burners either directly or by way of a pipe.

It is preferred that the distance p separating the upper edges of the air inlet holes 10 from the upper extremity of the first mixing tube 2 shall be not less than the internal diameter q of the constriction 8a.

With the arrangement hereinbefore described, initial mixing of the gas and air takes place in the first mixing tube 2, while further air is admitted through the inlet holes 10 provided in the tubular sleeve or gallery 9, the additional air passing into the second mixing tube 8 through the annular space 11 formed between the part conical end of the first mixing tube and the interiorly coned lower end of the second mixing tube while, due to the Venturi shape of the second mixing tube, a steady flow of air into both mixing tubes is entrained, the additional air mixing with the admixture of air and gas either in or issuing from the first mixing tube. In this way, the mixture has a very high air content, a large quantity of air being sucked in as a result of the injector action of the air and gas mixture issuing from the first mixing tube. Furthermore, it is found that it is virtually impossible to cause the burner to "light back" at the air admission holes or jet orifice and while having very high heating properties, the flame produced is stable and unaffected by draughts.

It has been found that when the gas control cock is turned low to a pilot light the flame is luminous, but as the cock is opened the flame is progressively aerated.

I claim:

1. A gas burner comprising in combination an air-gas mixing tube having a conical outer end and having a bore provided with an inwardly tapering throat and provided with air inlet openings through the wall of the bore which open to the interior of the tube immediately beneath the throat, the throat dividing the bore of the tube into two parts of different diameters, a gas jet fitted into the part of the air-gas mixing tube bore of larger diameter so as to be co-axial with the tube and terminating at its outlet adjacent the throat of the air-gas mixing tube and intermediate the larger and smaller bore-parts, the outer surface of the gas jet at its said extremity being also of tapering frusto-conical shape so that an axially inclined annular space is provided

between the jet and the throat, the width of said annular space being not less than one-sixth and not more than one-third of the diameter of the portion of the bore immediately thereabove an internally threaded sleeve carried by the first tube and arranged in concentric spaced relation with the outer conical end thereof and provided with air admission holes at its inner end, a second mixing tube having its inner end in threaded engagement with the threaded portion of the sleeve and having a bore and a Venturi throat in the bore, the throat of the venturi being arranged slightly beyond the outer end of the first tube while the inner part of the venturi surrounds the conical end of the first tube in spaced relation to provide a second inclined annular space which produces an ejector effect by which additional air may be drawn through the air admission holes into the air-gas mixture which issues from the said outlet end of the first mixing tube, and the distance between the upper edges of the holes in the sleeve and the outer extremity of the first mixing tube being not less than the internal diameter of the throat of the venturi.

2. A gas burner comprising in combination an air-gas mixing tube having a frusto-conical outer end and having an intermediate portion of the bore thereof provided with an inwardly tapering throat and provided with air inlet openings through its sides which open to the interior of the tube immediately beneath the throat, the throat dividing the bore of the tube into two parts of different diameters, a gas jet means fitted into the bore of the air-gas mixing tube of larger diameter so as to be coaxial with the tube and terminating at its outlet and centrally within the throat of the air-gas mixing tube and intermediate the larger and smaller ends of the said tube portion, the outer surface of the gas jet at its said extremity being also of tapering frusto-conical shape so that an axially inclined annular space is provided between the jet and the throat, the width of such annular space being not less than one-sixth nor more than one-third of the smaller diameter part of the said mixing tube, an internally threaded sleeve carried by the first tube and arranged in concentric spaced relation with the frusto-conical outer end thereof and provided with air admission holes at its inner end, a second mixing tube having its inner end in threaded engagement with the threaded portion of the sleeve and having a venturi shaped inner surface which is located relatively to the frusto-conical outer end of the first tube to provide a second inclined annular space which produces an ejector effect by which additional air may be drawn into the air-gas mixture which issues from the said outlet end of the first mixing tube.

3. A gas burner comprising in combination an air-gas mixing tube having a bore having portions of larger and smaller diameter and an inwardly tapering throat which merges at its ends into portions of the bore of larger and smaller diameter, a gas jet means fitting in the bore of larger diameter so as to be coaxial with the tube and having its extremity through which the gas issues disposed to terminate intermediate the ends of the said throat such that an axially inclined annular space is provided between the outer surface of the jet and the adjacent tapering throat of the bore, the width of such annular space being not less than one-sixth nor more than one-third of the smaller diameter part of the

said mixing tube, the wall of the portion of the mixing tube of larger diameter having openings therein immediately beneath the tapering throat through which air can be admitted into said annular space, a second mixing tube having a bore in the form of a venturi arranged as a coaxial extension of the first such tube and having its bore of larger diameter than that of the portion of the other tube which is of the smaller diameter, and means for connecting the said tube to the first tube comprising a sleeve carried by and surrounding the outlet end of the first mixing tube and having openings therein through which additional air is admitted into the second mixing tube, said sleeve being internally screw-threaded to receive an externally screw-threaded portion on the inner end of the second mixing tube.

4. A gas burner comprising in combination an air-gas mixing tube having a bore having portions of larger and smaller diameter and an inwardly tapering throat which merges at its ends into portions of the bore of larger and smaller diameter, a gas jet means fitted in the bore of larger diameter so as to be coaxial with the tube and having its extremity through which the gas issues disposed to terminate intermediate the ends of the said throat such that an axially inclined annular space is provided between the outer surface of the jet and the adjacent tapering throat of the bore, the width of such annular space being not less than one-sixth nor more than one-third of the smaller diameter part of the said mixing tube, the wall of the portion of the mixing tube of larger diameter having openings therein immediately beneath the tapering throat through which air can be admitted into said annular space, a second mixing tube having a bore in the form of a venturi arranged as a coaxial extension of the first such tube and having its bore of larger diameter than that of the portion of the other tube which is of the smaller diameter, and means for connecting the said second tube to the first tube, comprising a cylindrical sleeve integral with the first tube and arranged in spaced concentric relation with the outer end thereof and having openings therein through which the additional air is admitted into the second mixing tube, said sleeve being internally screw-threaded to receive an externally screw-threaded portion at the inner end of the second mixing tube.

ALBERT HORACE GREAVES.
